UNITED STATES PATENT OFFICE.

MICHAEL W. HANLEY, OF CHICAGO, ILLINOIS.

STOCK-RELEASING DEVICE.

SPECIFICATION forming part of Letters Patent No. 331,396, dated December 1, 1885.

Application filed June 19, 1884. Serial No. 135,446. (No model.)

To all whom it may concern:

Be it known that I, MICHAEL W. HANLEY, a citizen of the United States, and residing at Chicago, in the county of Cook and State of Illinois, have invented certain new and useful Improvements in Stock - Releasing Devices, which are fully set forth in the following specification, reference being had to the accompanying drawings, in which—

10 Figure 1 is the inside sectional view of a barn or stable with my improved stock-liberator. Fig. 2 is a plan section of the same, taken on line *x* *x*, Fig. 1, showing the operation of the liberator on two sets of stalls. Fig. 3 is a vertical section of the same, taken on line *y* *y*, Fig. 2. Fig. 4 is a detail elevation of part of the sleeve and sliding or locking bar. Fig. 5 is a plan section of the same on line *z* *z*, Fig. 4. Fig. 6 is a detail section of same as Fig. 4, 20 showing the parts locked with the alarm attached thereto. Fig. 7 is a detail elevation of the alarm and its connections. Fig. 8 is a detail elevation of the sliding or locking bar.

My invention relates to certain devices for 25 the purpose of liberating stock, horses, &c., which may be in a barn or stable at the time of a fire, and not only releases them from the stalls, but alarms them, causing them to run out of the stall. It also enables one man to liberate all the stock, be it one or one thousand head, in a very few seconds.

In the drawings, A is the stall or manger; B, the sleeve or tube through which the sliding or locking bar C works. E is the shaft for working the same, and N is the alarm.

By means of the mechanism which I have provided, the liberating of the stock may be done either from the inside or the outside of the building, or above or below the stable-room. 40 I will now proceed to explain my invention fully, reference being had to the accompanying drawings, which are a part hereof.

Running along the head of the stalls is the sleeve or tube B, arranged with openings *a* at 45 proper intervals—*i. e.*, one in the center of that length of sleeve which crosses each stall. In this sleeve or tube there is a sliding or locking bar, C, which runs the full length of the sleeve or tube. This bar is furnished with 50 hooks or fingers *b*, for catching and locking the rings to which the halters are fastened. The sliding bar fits tightly in the sleeve, and the

fingers are formed by cutting an L-shaped slot in the bar, the long arm of the slot being parallel to the longitudinal axis of the bar, and longer than the width of the opening *a* in the tube. At the end from which it is desired to operate the "liberator" the sliding bar C is connected with a shaft, E, with a screw-thread. There is a nut, D, fitted with a female screw-thread, through which the shaft E works. This nut is grooved on its outer circumference, and by means of this groove it is set in a fixed plate, which restricts any lateral motion of the nut. This nut is attached to the shaft E, which has on its outer end a hand-wheel, P, by which said nut is turned off and on the sliding bar, and as the nut D is held from longitudinal movement, it is obvious that the locking-bar C will be caused to slide in and out of the sleeve 70 B. The bar C is made with a spline or feather which runs in a groove in the sleeve B, and prevents the bar from turning. The bar and sleeve might both be made square or any suitable device used to prevent the bar from turning. 75

Attached to the nut-shaft E is a gear-wheel, J, which engages with the rack H, attached to the rod K. This rod moves forward and backward longitudinally in fixed bearings, and it 80 is at right angles to the sliding bar. As the rod runs by several rows of stalls, several shafts running in sleeves and having gears attached to them may be worked by the nut-shaft E and hand-wheel P, there being several racks attached to the rod K, each working a pinion attached to the nut-shafts E'.

If it would seem desirable to work the sliding bars either from above or below the floor on which the stalls are situated, the nut-shaft 90 may be furnished with a bevel-gear, L, which engages with a similar bevel-gear, M, on the end of a shaft extending above or below, as desired.

The cattle in the stable are tied by their 95 halter-straps to rings *h*. These rings are held by the fingers or hooks *b*, attached to the sliding bar C. When it is desired to put in the rings, the sliding bar is run into the sleeve, so as to carry the fingers *b* far enough along in 100 the opening *a* to allow the ring or link *h* to be hooked onto the finger. The sliding bar is then run forward again until the finger extends across the opening and the ring is held

in place. There is a rod, *c*, which is furnished with a hook, *d*, near its upper end, and a ring, *e*, at the lower end. The ringed end of the rod is fastened to the finger, together with the ring 5 to which the halter-straps are fastened. The other end of the rod fits into a socket hole in the wall or ceiling of the stall above it and at its head. To the hook, near the end of the rod, is hung a tin can, *N*, filled with stones. 10 When it is desired to liberate the stock, the sliding bar is run into the sleeve by the mechanism already described. As soon as the finger *b* has passed the opening *a* the ring *h*, to which the halter is tied, and also the ring *e* at 15 the end of the rod *c*, are released and fall to the ground by reason of their own weight. When the rod *c* falls the tin can *N* full of stones comes down at the horse's head and causes him to back out of the stall, thus letting him see that 20 he is free, and in the general confusion a stampede will naturally be made for the door, many head of stock or horses thus being saved that would otherwise be burned up in case of fire.

Having now fully described my invention, 25 what I claim as new, and desire to secure by Letters Patent, is—

1. In a stock-liberator, a sleeve or tube, *B*, running across the head or front of a row of stalls, and provided with small openings *a*, in 30 combination with the sliding bar *C*, provided with fingers *b*, for securing and holding the rings *h*, to which the halter-straps are fastened, the threaded shaft *E*, nut-shaft *E'*, nut *D*, and hand-wheel *P*, substantially in the manner and 35 for the purposes set forth.

2. The combination, in a stock-liberator, of the tube or sleeve *B*, extending across a row of stalls, and the sliding or locking bar *C*, nut *D*, threaded shaft *E*, nut-shaft *E'*, and hand-wheel *P*, for the purpose of sliding the locking-bar *C* within the tube *B*, with the rod *c*, provided with the hook *d*, by which the alarm *N* is held in position, and the ring *e*, by which the rod is held in place, together with the alarm *N*, substantially as and for the purposes 40 45 specified.

3. In a stock-liberator, the combination of the sleeve *B*, sliding bar *C*, nut *D*, threaded shaft *E*, nut-shaft *E'*, and hand-wheel *P*, for operating the sliding bar *C*, with the pinion *J*, 50 attached to the nut-shaft *E'*, and the rod *K*, provided with racks *H*, which engage with the pinion or gear *J*, and by means of which several sliding bars *C* may be simultaneously moved in sleeve *B*, substantially as and for the 55 purposes specified.

4. In a stock-liberator, the sleeve or tube *B*, arranged substantially as described, and provided with the openings *a*, in combination with the locking-bar *C*, arranged to slide within 60 said sleeve, and provided with fingers *b*, a threaded shaft, *E*, connected to the locking-bar, and a nut, *D*, and nut-shaft *E'*, for operating the threaded shaft and locking-bar, substantially as and for the purposes specified.

MICHAEL W. HANLEY.
